UNITED STATES PATENT OFFICE.

GILES CHRISTOPHER, OF LONE WOLF, OKLAHOMA TERRITORY, ASSIGNOR OF ONE-FOURTH TO COLEMAN R. CHRISTOPHER, ONE-FOURTH TO WILLIAM L. CHRISTOPHER, AND ONE-FOURTH TO DAN. E. CHRISTOPHER, OF LONE WOLF, OKLAHOMA TERRITORY.

BALING-PRESS FEEDER AND PACKER.

SPECIFICATION forming part of Letters Patent No. 786,873, dated April 11, 1905.

Application filed June 29, 1904. Serial No. 214,692.

To all whom it may concern:

Be it known that I, GILES CHRISTOPHER, a citizen of the United States, residing at Lone Wolf, in the county of Kiowa, Oklahoma Territory, have invented a new and useful Baling-Press Feeder and Packer, of which the following is a specification.

This invention relates to machines or devices for feeding material to cotton and other baling-presses and for packing or tramping the same in the press-box prior to final compression.

The invention has for its object to effect an even and automatic feed and supply of the material to be compressed and also to effect vertical reciprocation of a plunger, whereby the material fed shall be tramped and compacted within the press-box prior to final compression.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that no limitation is necessarily made to the precise structural details therein exhibited, but that the right is reserved to any changes, alterations, and modifications which come fairly within the scope of the invention and which may be resorted to without departing from the spirit or sacrificing the efficiency of the same.

In said drawings, Figure 1 is a general side elevation, partly in section, of a machine constructed in accordance with the principles of the invention. Fig. 2 is a detail view of the spring-actuated cam whereby the valve mechanism is operated. Fig. 3 is a sectional elevation taken on the line 3-3 in Fig. 1. Fig. 4 is a longitudinal vertical sectional view of the feeder. Fig. 5 is a detail perspective view of

a portion of one of the feeder-slats, showing one of the spring-actuated teeth.

Corresponding parts in the several figures are indicated by similar numerals of reference.

My invention is specially applicable to so-called "double" presses, in which material is fed into one press-box while the bale in the other press-box is composed, compressed, tied, and ejected. In the accompanying drawings, however, I have shown the invention applied to a single press-box only, inasmuch as the compressing means and the means for shifting the position of the press-boxes are no part of the invention.

In the present embodiment of the invention a platform 1 is disposed above a packing-chamber 2, beneath which the press-box 3 is located. Directly above the packing-chamber the platform 1 supports a cylinder 4, in which reciprocates a piston 5, having a stem 6, carrying a plunger or packer head 7, adapted to reciprocate within the packing-chamber and the upper end of the press-box. The packer-head may be provided with an upwardly-extending plate 8, adapted to form a closure for the feeder 9, which is connected, as shown, with one side of the packing-chamber.

Supported upon the platform 1 adjacent to the cylinder 4 is a frame 10, having bearings for several shafts. One of these shafts, 11, carries a drum or pulley 12, which receives motion by means of a belt or band 13 from a line-shaft. (Not shown.) The shaft 11 also carries a pinion 14, meshing with a spur-wheel 15 upon a shaft 16, disposed below the shaft 11. The frame 11 is erected upon a massive base 17, which is provided with a slot or which may be otherwise constructed to support a pivotally-mounted cam 18, the operative face of which is forced in the direction of pins 19, mounted in the face of the spur-wheel, by the action of a spring 20, coiled upon a link-rod 21, which is connected pivotally with an arm 22, extending downwardly from the lower pivoted end of the cam and having at its

outer end a button 23, against which the outer end of the coiled spring 20 presses. The inner end of said spring presses against the base 17, thus causing the spring to exercise pressure 5 in the proper direction. The piston within the cylinder may be operated by any desired fluid-pressure. In the accompanying drawings has been illustrated a valve-casing 24, from which pipes 25 and 26 are led, communicating, respectively, with the lower end and the upper end of the cylinder. The valve-casing is also provided with a fluid-inlet 27 and with an exhaust 28. Within the valve-casing 24 is mounted a rotary controlling-valve 29, provided with arcuate ports 30 and 31. In one position of the valve the port 30 establishes communication between the fluid-inlet 27 and the pipe 26, which supplies fluid to the upper portion of the cylinder, while 15 the port 31 establishes communication between the pipe 25, connecting with the lower portion of the cylinder, and the exhaust. When the position of the valve is shifted, the upper end of the cylinder will be connected, through 20 the port 30, with the exhaust, while the lower end of the cylinder will be connected, through the port 31, with the fluid-inlet. It is thus obvious that by partially rotating the valve to the extent of only one-fourth of a revolution 25 the motive fluid will be alternately supplied to and exhausted from each end of the cylinder, thus driving the piston in opposite directions to reciprocate the packer-head 7.

The valve 29 is provided with an operating-stem 32, one end of which is connected by a link-rod 33 with the free end of the cam member 18. The operative face or edge of the latter is composed of an approximately-semi-circular depression 33' near the lower end 40 thereof, the upper edge of said depression terminating in the apex 34, from which wave-like depressions 35 recede in the direction of the point or upper extremity 36 of the cam.

The pins 19, whereby the cam is actuated, 45 are screwed into the face of the spur-wheel 15, near the rim of the latter, and said pins will successively engage the operative face of the cam, thereby throwing the latter against the tension of the spring 20, so as to cause the 50 valve to be "opened," thereby meaning that when the upper end of the cylinder is placed in communication with the fluid-inlet the opening of the valve is effected suddenly and swiftly by reason of one of the pins contact- 55 ing with the upper wall of the recess 33', thereby quickly throwing the cam in the direction indicated by an arrow A in Fig. 1. As the rotation of the spur-wheel 15 proceeds the pin will gradually pass from the wave-like depre- 60 sions 35 of the cam and finally out of contact with the latter, the cam being thus gradually restored to its normal position and the reversal of the valve being thus effected gradually and comparatively slowly. The opera- 65 tion of the packer is thereby rendered more

effective, since the material packed within the press-box will not be permitted to rebound suddenly while the packer-head gradually recedes from the press-box.

The feeder-casing 9, which is connected, as 70 described, with one side of the packing-chamber, contains an endless carrier 37, which may consist of chains 38, connected by slats 39, said chains being mounted upon sprocket-wheels 40 upon shafts 41 and 42 near the upper and lower ends of the feeder-casing. Motion may be transmitted to the shaft 42 from the shaft 16 by means of a suitably-mounted shaft 43, connected with the shafts 16 and 42 by miter-gearing 43' 44. The slats 39 of the 80 feeder are provided with staples 45, with which are pivotally connected teeth 46, which are normally held in an upright direction by means of a suitably-disposed spring 47. At the discharge end of the feeder-casing is arranged a stripping-rod 48, by contact with which the spring-supported teeth will be caused to swing, being thus stripped of the material, which is conveyed by the carrier to the packing-chamber. The feeder-casing may 90 be suitably connected with any source of supply--such as, for instance, the condenser of a cotton-gin.

The operation of this invention and its advantages will be readily understood from the foregoing description, taken in connection with the drawings hereto annexed. When the machine is in operation, the controlling-valve is normally in what I term a "closed" position--i. e., in a position in which the upper end of the cylinder is open to the exhaust--while the lower end of the cylinder is connected with a source of fluid-supply, thereby retaining the piston and the packer-head in a raised position. The feeder is continuously 100 operated by the means herein described. When one of the pins 19 comes into contact with the operative face of the valve-actuating cam, the latter will be moved very slowly until the upper portion of the recess 33 is 110 reached, when it will be suddenly and swiftly thrown to a position in which the valve will be reversed or shifted to an open position, when the lower portion of the cylinder will be connected with the exhaust, while its upper portion will be connected with the source of fluid-supply, thereby causing the piston and the packer-head to descend. As the packer-head descends the plate 8 will cut off the supply from the feeder-casing, so that 115 no material will be fed above the packer-head. As soon as the operating-pin passes over the wave-like depressions 35 and out of the contact with the cam the latter will be restored by the spring 20 to its normal position, the 120 valve will be shifted, and the piston and packer-head will ascend and remain supported in a raised position until the cam 18 is again actuated.

By using a spur-wheel 15 of proper diameter 130

ter and causing the same to be rotated at a proper rate of speed and by causing the feed to progress evenly and at the desired rate of speed the necessary amount of material to 5 make a bale may be supplied to the press-box during a single rotation of the said spur-wheel, and the latter may of course be provided with any desired number of pins, so that the cam shall be actuated any desired 10 number of times for the purpose of effecting the tramping of the material within the press-box as often as may be necessary. In such case I may elect to space the pins 19 differently and progressively from the rim of the 15 wheel 15, the first pin in the cycle being nearest the axis of the shaft 16, while the remaining pins are gradually set outward toward the rim of the wheel. The effect of this arrangement will be to cause the valve at first 20 to be only partially oscillated, thus partly obstructing the passage of the motive fluid, and consequently causing the packer-head to be operated under a less degree of pressure while the press-box is comparatively empty. 25 As the operation progresses, however, the valve will gradually be opened more widely until at the end of the operation, when the press-box is full, the piston and packer-head will be operated under a maximum degree of 30 pressure. In Fig. 1 of the drawings I have shown the actuating-pins 19 thus set at different distances from the rim of the wheel. It is to be understood, however, that the proportions may be changed and that a larger 35 number of pins may be used to cause the valve to be operated with the necessary frequency.

Having thus described the invention, what is claimed is--

1. In a device of the class described, a press- 40 box, a fluid-operated packer, a controlling-valve, a press-feeder, a driven shaft, means for transmitting motion from the latter to the feeder, a wheel upon said driven shaft, pins

extending from the face of said wheel, a cam disposed in the path of said pins, and a link 45 connecting said cam with the stem of the controlling-valve.

2. In a device of the class described, a press-box, a fluid-operated packer, a controlling-valve, a press-feeder, a driven shaft, means 50 for transmitting motion from the latter to the feeder, a disk upon said driven shaft having pins projecting from the face thereof, a spring-actuated cam disposed in the path of said pins, and a link connecting said cam with the stem 55 of the controlling-valve.

3. In a device of the class described, a press-box, a fluid-operated packer, a controlling-valve, a press-feeder, a driven shaft, means 60 for transmitting motion from the latter to the feeder, a disk upon the driven shaft, pins projecting from the face of said disk and progressively spaced from the rim of the latter, and a valve-operating cam disposed in the 65 path of said pins.

4. In a device of the class described, a press-box, a fluid-operated packer, a controlling-valve, a press-feeder, a driven shaft, means for transmitting motion from the latter to the feeder, a disk upon the driven shaft, pins 70 projecting from the face of said disk, a valve-operating cam disposed in the path of said pins and having an approximately semicircular recess terminating in an apex and wave-like depressions extending from said apex to 75 the point of the cam, and means for forcing said cam in the direction of the operating-pins.

In testimony that I claim the foregoing as my own I have hereto affixed my signature in 80 the presence of two witnesses.

GILES CHRISTOPHER.
